2 SHEETS—SHEET 2.

UNITED STATES PATENT OFFICE.

HENRY EDWARD FROMBERG, OF CRANDALL, SOUTH DAKOTA.

MUSIC-LEAF TURNER.

1,302,355.

Specification of Letters Patent. Patented Apr. 29, 1919.

Application filed August 27, 1917. Serial No. 188,510.

To all whom it may concern:

Be it known that I, HENRY E. FROMBERG, a citizen of the United States, residing at Crandall, in the county of Day, State of 5 South Dakota, have invented certain new and useful Improvements in Music-Leaf Turners; and I do hereby declare the following to be a full, clear, and exact description of the invention, such as will enable others 10 skilled in the art to which it appertains to make and use the same.

This invention relates to improvements in music leaf turners, and has for its primary object to provide a device by means of which 15 a sheet or leaf of music may be turned from one side to the other of the music support.

A further object of the invention is to provide a device of this character which is foldable into compact form for the purpose 20 of rendering it readily portable.

Referring to the drawings,

Figure 1 is an elevation of the device in its operative position.

Fig. 2 is a sectional view on the line 2—2 25 of Fig. 1.

Fig. 3 is a sectional view on the line 3—3 of Fig. 1.

Fig. 4 is a detail perspective view of the 30 operating lever,

Fig. 5 is a detail view of a portion of the operating mechanism,

Fig. 6 is a detail view of one of the sheet 35 turning arms.

Fig. 7 is a detail perspective view of the upper pivoted bearing members for the turning shaft.

Fig. 8 is a detail perspective view of the lower bearing plate for the turning shaft, which also is formed to provide a guide for 40 the operating cords.

Referring more particularly to the drawings, 1 represents a casing which is formed of substantially equal shallow sections mounted upon the hinges 2, so that the casing 45 may be closed, and when covered with suitable leather or other material, will have somewhat the appearance of a music case. Mounted within one of the sections of the casing 1 is a lower bearing device 3 and 50 an upper bearing 4. The upper bearing 4 is hinged upon a plate 5 which is pivotally secured to the inside horizontal face of the upper side of the casing section, so that the bearing 4 may be swung so as to 55 lie wholly within the section or may be

projected therefrom. The lower bearing 3 is pivoted upon the lower side of the casing section, directly below the bearing 4, and is also intended to swing into the section or outwardly into vertical alinement with the 60 bearing 4. Bearing openings 6 in the lower and upper bearings 3 and 4 provide supports for a vertical wire or spindle 7 which is adapted to be stepped into the lower bearing 3, and then inserted into the upper bearing 4 by lifting the hinged bearing and inserting the end of the spindle into the opening 6.

Within the opposite casing section, and secured to the upper and lower sides thereof, 70 are the bearings 8 within which are hingedly mounted the resilient arms 9. The upper arm 9 is adapted to be projected across the joint between the casing sections, and looped over the upper end of the spindle 7 when the 75 latter is projected through the bearing 4 thereby locking the bearing 4 over the spindle. The lower arm 9 is provided with a looped end and is also adapted to be projected across the joint between the casing 80 sections, and is then looped over the lower end of the spindle, thereby locking the lower bearing 3 in its extended position, and also locking the spindle 7 within the bearing. The spindle 7 provides the hinge support for a pair of leaf holding frames 10. Each of the frames 10 consists of a wire element shaped into three sides of a rectangular structure whose fourth side is formed by a bracing element 11. The free ends of the 85 wire lengths are shaped into the hinge coils 12 which are received over the ends of the spindles 7, and when the hinge coils are assembled it is to be noted that one of them is spaced from the other on the spindle so 90 that coil springs 13 may be interposed between the hinge coils and have its ends so connected to the latter that under normal conditions the frames 10 are thrown together. The coils 12 are held in their recited spaced relation on the spindle or shaft 100 7 by collars 12^a secured on the spindle or shaft at the outer sides of each pair of adjacent coils. Furthermore, the frames 10 are shaped into the spaced fingers 14 which 105 provide around the edge of the frames more extended bearings for the proper retention of a sheet of music.

Upon the lower side of the edge of the casing sections, there is hinged a bracket 14' 110

so that it may be dropped vertically below the casing, or else swung entirely into the latter. Each of the brackets 14' is stamped from sheet metal, and its outer or free end is 5 provided with a pair of upturned ears 15 which are so shaped as to provide a snap notch therebetween within which the shank 16 of an angularly shaped support 17 may be engaged, the free end of the shank or 10 stem 16 being hooked as at 18, to be adjustably inserted in one of a series of openings 19 stamped into the body of the bracket 14'. The lower end of the angularly shaped bracket 17 provides a bearing for a lever 15 arm 20 whose forward end is provided with a finger hold 20'. Adjacent its forward end, the lever 20 has secured thereto one end of a cable 21 which passes thence through a guide loop 22 formed on the upper end of the corner 15 responding bracket 16, and is then secured at 21^a to a properly selected point on the lower member of the frame 10. The second half of the cable 21 is then passed in like manner through the opposite bracket 16 and connected to the forward end of the opposite lever arm 20. In its course, however, the cable 21 is passed through an arcuate guide groove 23 which is shaped upon the forward end of the lower bracket 3, by shaping the 25 edge of the metal into an outturned arcuate channel. The point of connection 21^a of the cable 21 to the frame 10 is chosen so that it moves practically in the path of the groove or channel 23 when the frame is swung from 30 one side to the other, the cable being thereby properly retained in the bearing, and exerting a constant operative pull upon the frame when one or the other of the operating handles 20 is actuated.

40 The manner of unfolding and setting up the music leaf turner has been clearly brought out in the course of the foregoing description. In using the device, a sheet of music is placed between the frames 10 where it is held by means of the tension exerted by the springs 13. Then, the first 45 page of the music having been played, the left hand lever 20 is depressed, thereby drawing the cable 21 from right to left. This action, by reason of the fact that the cable is guided over the groove 23, swings the frame 10 out of the right hand casing section, and carries it into the left hand side. To turn the leaf back into its original

position, the operation is repeated by the use 55 of the right hand lever 20.

From the foregoing description, it will be apparent that I have provided a very simple and practical device for conveniently and effectively turning sheets of music, and that 60 it may also be employed for carrying music to the place of performance.

What I claim as my invention is:—

1. A music leaf turner comprising a support, a shaft carried thereby, a frame journaled on the shaft at spaced points, a second frame journaled on the shaft at points spaced outwardly of the first frame, coil springs on the shaft between adjacent pairs of turning points and having their ends engageable with the frames to resiliently urge them together, and means for turning said frames simultaneously on the shaft. 65 70

2. A music leaf turner comprising a support, a shaft carried thereby, a pair of 75 frames each formed of a single length of wire bent in substantially U-shape, braces connecting the legs of said wires adjacent their inner ends, the inner ends of the legs of one frame being inwardly offset, journal 80 connections between the inner ends of the legs and the shaft, a coil spring disposed between each offset leg portion of one frame and the adjacent leg portion of the other frame, and having its ends bearing against 85 said frames, to urge them together and means for simultaneously turning said frames on the shaft.

3. A music leaf turner comprising a pair 90 of hingedly connected casing sections, a shaft mounted within said sections adjacent their hinge connection, a turnable frame on the shaft, bars hinged to the lower edges of the sections and adapted to swing thereinto and to depend from said sections when open, 95 operating levers hinged to the free ends of said sections, guide members at the inner ends of the sections and a cable secured to the operating levers and extended through the guide members and connected with the 100 turning frame.

In testimony whereof, I affix my signature in the presence of two witnesses.

HENRY EDWARD FROMBERG.
